UNITED STATES PATENT OFFICE.

EDWARD WESTON, OF HILLSIDE, NEW JERSEY.

SWITCH.

Application filed July 21, 1916. Serial No. 110,521.

To all whom it may concern:

Be it known that I, EDWARD WESTON, a subject of the King of Great Britain, residing at Hillside, in the county of Union and State of New Jersey, have invented certain new and useful Improvements in Switches, of which the following is a specification.

My invention relates to improvements in electric switches, and is primarily designed 10 for use in connection with the lighting and ignition systems of automobiles.

In the particular embodiment shown one switch controls the lighting circuit and a second switch controls the ignition circuit, 15 and a single locking device is arranged to lock both switching mechanisms in any adjusted position; or to unlock them so that the switches may be freely operated. Such a combination of parts is well known in the 20 art, my invention relating to such an arrangement of the parts and to such particular constructions that a simple, compact, cheap, durable, and effective device is obtained. The particular improvements which

25 I have devised relate to a new mode of combination of the locking and switching mechanisms; to a new form of key-operated locking device for the switch mechanism; to a new spring structure; to a new form of 30 rotatable switch body on which the spring structure is secured; to new forms of escutcheon plate and cell or back plate; to a cell or back plate carrying the necessary connections, preferably molded therein, and 35 having on its front and back locating, guiding and holding projections or depressions, preferably formed therein and thereon by molding; to new or improved methods of securing in place the connecting pieces, bolts, 40 studs and other kindred devices; to the manner of mounting rotatably the switch and locking mechanisms between the escutcheon plate and the cell plate; to the shaping of the various parts so that they can be manufactured cheaply and readily assembled; and 45 to various other features which will appear from the accompanying drawings, specifications and claims.

In the drawings Fig. 1 is an elevation 50 of the instrument.

Fig. 2 is a side view of Fig. 1.

Fig. 3 is a back view, with the cell or base plate removed.

Fig. 4 is a plan of the back or outside 55 face of the cell or base plate.

Fig. 5 is a side view of the cell or base plate, one half being shown in section on plane V—V of Fig. 4.

Fig. 6 is a plan of the front or inside face of the cell or base plate. 60

Fig. 7 is a detail showing the manner in which the contact devices are held in place and secured against rotation.

Fig. 8 is a section on plane VIII—VIII of Fig. 6. 65

Fig. 9 is a plan view of the key.

Fig. 10 is a sectional elevation of a connector or cable terminal.

Fig. 11 is a section on plane XI—XI of Fig. 1, the parts being shown on a larger 70 scale.

Fig. 12 is a plan of the spring structure.

Fig. 13 is a section on plane XIII—XIII of Fig. 12. 75

Fig. 14 is a side elevation of the rotatable switch body shown in Fig. 11.

Fig. 15 is a bottom plan view of Fig. 14.

Fig. 16 is a detail of the locking bolt and cooperating aperture. 80

Fig. 17 is a sectional elevation of parts of Fig. 16.

Fig. 18 is a section on plane XVIII—XVIII in Fig. 3, the parts being shown on a larger scale.

Fig. 19 is a section on plane XIX of Fig. 1. 85

Figs. 20 and 21 are plan and side views of a modification.

Figs. 22, 23 and 24 are bottom plan and end views of a second modification. 90

Figs. 25 and 26 are plan and end views of a third modification.

Figs. 27 and 28 are plan and side views of a fourth modification.

Figs. 29, 30 and 31 are side, plan and end views of a fifth modification. 95

Figs. 32 and 33 are plan and end views of a modified form of combined indexing and locking device; and

Fig. 34 is a modification of the device 100 shown in Fig. 33.

The switching device as a whole comprises a front or escutcheon plate 1, a base or cell plate 2, and switches and locking mechanism therefor rotatably mounted or held between the escutcheon plate and the base plate. 105

The base or cell plate consists of a block of insulating material, having an upwardly extending flange 4, and is provided with 110

perforated ears 5, by which it is attached to the escutcheon plate. Molded into the body of the block are a number of contact devices 8, each of these devices consisting 5 of a hollow body flanged at each end, so that they are fixedly held in, while extending through the block. The exterior of the cylindrical portion 9 is knurled or provided with longitudinal ribs or other means for 10 preventing rotation, which when molded into place prevent rotation of the contact devices. The interior cavity is screw-threaded as at 10, to receive a binding screw and at its other end has a beveled or curved 15 wall 11, to form a seat for the ball contacts of the spring member of the switch to be later described, thereby affording not only a good electrical connection, but also serving as devices for indexing the locking apertures in the switch body with relation to the 20 locking bolt.

The front surface portion of the cell plate is provided with cavities 13, and 14, into 25 which extend without contact screws 47 of the switches. 16, 16, are downwardly curved or inclined holding or indexing depressions arranged in the circular path of movement of the ball contacts of the spring member. These ball contacts rest in these cavities 16 30 when the switch is in the off-position, these depressions serving to index the locking cavities of the switches in this off-position. Extending radially through the arc-path over which the ball contacts move are 35 grooves 17, which prevent conductive connection between adjacent contact devices which might occur because of the fine particles of metal being rubbed off from the ball contact and forming a conductive film on the 40 surface of the plate. The front surface of the plate is level except for a centrally arranged inwardly extending tongue 18 preferably formed integrally with the base plate and having therein a chamber 19 to receive 45 the barrel of the lock, and a shallow cavity 20, the rim 65, of which acts as a bearing for the oscillatable locking bolt 31 (Fig. 3), of the lock.

21 and 22 are arc-shaped grooves, within 50 which move pins 23, secured to the body of the rotatable switches, the ends of the grooves serving as limiting stops to prevent over rotation.

24 is a circular surface provided to receive 55 the casing or barrel of an indicator, with which the device may be provided.

15 is a curved surface concentric with the axis of rotation of the key, to prevent the bit of the key dropping down below the bottom of the slot 15' in the escutcheon plate, and thus preventing easy withdrawal of the 60 key.

As shown in Figs. 5 and 7 the ends of the contact pieces 8 project beyond the back 65 surface of the block and adjacent to these

projections are molded lugs 25 or other means formed on or in the plate to serve as cooperating members to prevent rotation of the particular form of coupling device, or cable terminal 26, shown in detail in Fig. 70 75 75 27, 27, preferably molded integrally with the plate and serving as locating stops for the safety cut-out device (not herein shown) which is secured to the plate by a screw passing through the contact device 8'. 29 is a projection formed during the molding and constituting a closure for the chamber 19. 80

The flange 4 serves not only as a closure or wall for the space within which are located the operative parts of the switches and the locking bolt, but also serves as a strengthening or stiffening rib to prevent any bending of the plate under pressure which might be applied during the operation of the switches. 85

Each of the rotatable switch members consists of a body portion or hub 32 having 90 a finger piece 33, preferably formed or molded integrally therewith, and each is provided with a flange 34 which is of greater diameter than the flanged opening in the escutcheon plate 1. The application 95 of a little oil or grease to this flange makes the joint between the switch body and the escutcheon plate practically water-tight. In the flange 34 (Figs. 14 and 15) are provided a series of locking grooves or apertures 35, 100 36, 37, 38, 39 (see Fig. 15) for receiving a tongue 40 (Fig. 16) forming part of the pivoted locking bolt 31. These locking grooves do not extend entirely through the flange, thus leaving a web portion 90 which serves 105 not only as a means for preventing ingress of water, but also as a strengthening web. The body portion 32 is also provided with a preferably integral projection or boss of less diameter than the flange 34, and in this 110 boss are formed or molded five grooves 41, 42, 43, 44 and 45. Secured in the material of the body portion and centrally of the groove 44 is a pin 23. The body portion 32 also has centrally secured thereto, and preferably by molding thereinto, a screw-threaded 115 socket 46 for receiving the screw 47 by which the spring structure may be secured to the body portion. The cylindrical head of the screw projects into one of the corresponding openings 13 or 14 in the cell plate. The inner flange of this socket 46 is knurled, so that when molded into the body portion of the switch member, rotation of the socket 120 is impossible. Each of the rotatable switch members, is for the sake of interchangeability, made identical although obviously the locking apertures on the outer sides of each 125 switch perform no function. It is, however, cheaper to make the switch bodies all alike, 130

as only one set of molding dies is required. A spring structure, see Figures 12 and 13, is preferably made of phosphor bronze, formed as a single piece having three open 5 sector-shaped arms 48, 49, 50, which are given an initial upward bend or set (as shown in Fig. 13) and a flat driving arm 51 having a perforation through which extends the pin 23.

- 10 The circumferential parts of the sector-shaped arms are provided with curved ball portions 52, 53, 54, preferably extending inwardly into the sector-shaped openings, these ball portions being also preferably formed integrally with the rest of the 15 spring structure.

This form of spring structure has been found to be particularly effective both mechanically and electrically. Each ball portion 20 is carried at what are practically the ends of 2 L-shaped arms so that each is mounted at the end of two united springs having a radial and a circumferential portion, the spring effect thus produced being 25 due to the combined effect of both arms, which are, however, by the arrangement described brought into an exceedingly compact relation to each other so that a minimum amount of space is occupied by the 30 spring arms. The symmetrical arrangement of the radial arms on each side of the ball insures that the ball will accurately register with the holding or indexing cavities 16, as well as with the contact pieces 8 to make a 35 firm electrical connection. The double arm construction also provides ample conductivity so that the waste of electrical energy is minimized. The spring structure is assembled on the body of the rotatable switch 40 member by passing the pin 23 through the aperture in the arm 51 and then securing the whole structure to the body of the switch by means of the screw 47. The radial arms of the sector-shaped switch members rest 45 in the corresponding grooves in the boss. The spring structure is positively driven by engagement of the pin 23 with the arm 51.

The whole rotatable switch member is 50 journaled at its front portion by the engagement of the body portion 32, with the flange 76 of the escutcheon plate, and is held in place without further fastenings when the cell plate is secured to the escutcheon plate by screwing the nuts 58 onto the screw studs 55 59 which are riveted to the escutcheon plate.

The screw stud 59 (see Fig. 3) is prevented from turning by the provision of corresponding flat sides on the screw stud and in the opening in the escutcheon plate.

60 As shown in Fig. 11, the portions 56 of the boss on the body 32 do not extend quite into contact with the bottom of the cell plate, so that the switch member can during operation, be pressed inwards slightly 65 against the pressure of the spring system,

while at the same time an inward movement of sufficient amplitude to distort or injure the springs is prevented.

The locking device consists of a two armed key-operated oscillatable locking bolt 70 31 provided with means for engaging the corresponding locking parts of the rotatable switch member. In this case these locking members are shown as locking tongues 40, one near each end of the locking bolt and 75 extending in opposite directions. This bolt is stamped out of spring steel and is provided at each end with a curved member 60 (see Figs. 16 and 17), which snaps over a smooth curved or inclined head of an abutment, consisting of a curved or inclined head of a rivet 61 secured to the escutcheon plate.

The locking bolt 31 is mounted to oscillate on a stud 62 also riveted to the escutcheon plate. To provide a bearing on the bolt, there is secured thereon (see Fig. 18), a flanged hub 63 having a central aperture fitting the stud 62, this hub being preferably counterbored to avoid possibility of contact 80 with the staked portion of the stud 62. To assemble the bolt and its hub the central aperture in the locking bolt is located on the shank of the hub, a washer 65' is slipped over the shank, and the end of the hub is then 85 as shown at 64, staked over the washer, thus firmly clamping together as one structure the locking bolt 31 and the hub 63. The washer 65' rests on the rim 65 on the projecting tongue 18 of the cell plate.

The locking bolt 31 is operated by a flat key 66 (see Fig. 9) having a bit 67, which engages the walls of a cavity 68 in the locking bolt. The walls of this cavity 68 are so shaped that the bit 67, of the key, when rotated, will engage one or the other of the walls to cause an initial angular movement of the locking bolt and may then continue its movement freely, after disengagement with the wall, in the same direction.

A slotted barrel 69' (Fig. 18) fits into the cavity 19 in the cell plate and has a retaining flange 72 resting against the back of the escutcheon plate. This flange also serving as a stop for undue rotation of the locking bolt by engagement with the shoulders 69, 70. Rotation of the key in one direction will cause the locking bolt to swing so that its tongues 40 will engage in the locking apertures of the switch member, the rounded ends 60 of the locking bolt snapping over the curved or inclined abutments 61, 61. Movement of the key in the other or unlocking direction, will cause an opposite movement of the locking bolt whose end 60 again snaps over the head of the abutment but in a reversed direction. The locking bolt is thus prevented from accidental disengagement from the locking position, the abutment acting as a stop except when by 100 105 110 115 120 125 130

operation of the key, the locking bolt is positively moved over it, and conversely, the abutment prevents engagement of the locking bolt with the locking apertures except by positive operation of the key.

In its disengaged position, the locking bolt, though freely rotatable about its pivot, has one end, as will be apparent from Fig. 3, located between the upper abutment 61, and 10 the inner wall of the cell plate, an additional stop against undue rotation being thus provided. It will be noted that (see Figs. 16 and 17) under the transverse pressure of the spring locking bolt, the curved underside of 15 the part 60 thereof will be forced down either side of the abutment, thus giving the locking bolt a positive movement (independent of the movement produced by the key) in each direction. The key only serves 20 to bring the locking bolt over the apex of the abutment head, the spring action driving the tongue of the bolt into the locking apertures on the one hand, and, on the other, moving the locking bolt to such an angular 25 position that the free entrance of the bit of the key into the cavity 68 is insured. Otherwise, the shoulder 70 might come into the path of movement of the key-bit and prevent operation of the key.

Shoulders 69 and 70 on the bolt prevent 30 operation of the bolt by rotation of the key in the wrong direction.

The locking apertures in the rotatable switch member are beveled at their outer 35 ends to insure an easy entrance of the locking tongues, but once the tongues are in locking position, it is impossible, owing to the disposition of the tongues and apertures, at an angle to the axis of the bolt and 40 to the radius of the rotating switch member, to unlock the bolt by any attempted rotation of the switch members.

A similar spring-driving action may be attained by other means. Thus as shown in 45 Figs. 20 and 21, a holding spring 104 may be suitably mounted against rotation by its central flat sided aperture engaging the flattened sides of the top of the pivot pin 62', the spring being provided with downwardly 50 extending inclined side flanges 105 and 106. As shown in Fig. 20, the flange 106 is holding the locking bolt in the locking position, while the flange 105 has ridden up and rests on the top of the locking bolt 31'. When 55 the bolt is turned into the unlocked position, the flange 105 drops over the edge of the locking bolt and acts by reason of its inclination to complete the movement of the bolt, while the flange 106 rides up onto the 60 top of the bolt.

As shown in Figs. 22, 23 and 24, a spring device 107 may be loosely mounted on the pivot stud beneath the locking bolt and has upturned ears 108 engaging the sides of the 65 locking bolt so that as the locking bolt

moves the spring moves with it. The end of the spring device 107 has a V-shaped member 109 at its outer end which engages corresponding notches formed in the escutcheon plate.

Or, as shown in Figs. 25 and 26, the locking bolt may have secured thereto at one end a pair of springs 100 and 101, the ends of which are arranged to pass over and under an abutment device 61', oblong in cross section and secured to the escutcheon plate.

Or, as shown in Figs. 27 and 28, the locking bolt itself may be made of two similar parts 102, 103, each of spring metal and riveted together. The ends of these parts 102, 103, similarly engage an abutment device 61' having an oblong cross section. Still another form of this device is shown in Figs. 29, 30 and 31. The end 110 of the locking bolt is oblong in cross section and arranged to pass between the curved ends of a pair of stationary springs, 111, 112, secured to the escutcheon plate.

In all of these forms of device for obtaining the spring snap action of the locking bolt, there are provided cooperating curved or inclined surfaces, one fixed to the escutcheon plate and the other to the locking bolt, spring pressure being applied to one or the other of the surfaces so that the locking bolt will be moved by the positive action of the key and the spring snap action as above described, and will be held in its locked or unlocked position by the stationary arrangement acting as an abutment until forcibly moved therefrom by the key.

The escutcheon plate is of the shape shown in Figs. 1 and 19, from which the construction will be apparent. The depressed portion 75 is designed to receive a current direction indicator, not shown herein, but described in a contemporaneously filed application. This plate has riveted thereto the attaching screw studs 59, 59'; the pivot stud, 62, for the locking bolt; and the rivets whose heads form the abutment stops 61, 61'. This plate has outwardly extending flanges 76 surrounding the openings through which extend the finger pieces 33, 33' of the switches.

A convenient form of circuit connector or cable terminal 26 is shown in Fig. 10. It has a slotted piece portion provided with double, side flanges 26', the slot permitting the insertion of a holding screw, and the flanges 26' embracing the sides of the lugs 25 on the cell plate to prevent rotation of the connector when the holding screw is screwed up. The ends of the insulated conducting cables are brought in between the flanges 82 which are then bent around the insulation, while the bared end of the cable or conductor is embraced by the bent over ears or lugs 83 and soldered to the terminal.

The operation of the device will be largely apparent from the foregoing detailed description of the parts. By operating the key the locking bolt will be shifted from the locking position shown in Fig. 3, the curved ends of the bolt snapping over the heads 61 into the unlocked position. The switches can then be manipulated by the finger pieces, the balls 52, 53 and 54 of the spring structure seating themselves either in the holding cavities 16 in the off-position of the switch or in the cavities in the heads of the connecting pieces 8, or 8' (as shown in Fig. 11), in the on-position of the switch.

When locked no sufficient force can be exerted manually on the finger pieces either to cause rotation of the switches or to cause displacement, distortion or other injury to the bolt or other parts of the locking mechanism. Any force which is exerted on the locking bolt is exerted directly along the axis of the locking bolt, either as a push or pull against the pivot, and the locking bolt while light is abundantly able to withstand any pressure so applied. It will be noted that either of the switches can be locked in any of its positions and for this purpose it is essential that the locking apertures in the switch body shall be exactly in position to permit engagement with the locking tongues of the bolt. This "indexing" action is secured by means of the accurate location of the contact members 8, 8', and the holding cavities 16 on the cell or base plate, in which seat themselves the ball portions of the springs which are in turn exactly located on the switch body with reference to the locking apertures. As the switches are rotated, the operator can readily feel and hear when the switch arrives at any of the stop positions and in any of these positions the key can be operated to lock or unlock the switches. The operator cannot, however, unduly rotate the switches as the pins 23 and slots 21, 22 limit the range of movement.

Other forms of the combined indexing and locking mechanisms may be used, two such forms being indicated in Figs. 32, 33 and 34. In Figs. 32 and 33, the rotating switch members A and B are provided at the proper points with notches. Bearing against the peripheries of the switch members are two outwardly spring pressed arms C and D, having at their end heads E and F, the outer surfaces of which are shaped to correspond with the notches in the switch members, while the inner surfaces of the heads are curved to correspond with the curvature of a locking bolt G arranged to be operated by a key. The locking bolt G, has an arm G', having at its ends a ball or other means for engaging properly located cooperating holding means G'', which may be properly shaped cavities in the escutcheon plate.

When the heads E and F are in the position shown, the switch members are properly indexed. If the heads F and G are not in the position shown, the lock bolt cannot operate, as its ends will engage the shoulders on the heads.

In Fig. 34, is shown a similar construction except that the spring H has its ends E', F', formed to act as indexing means, the locking being of similar construction and mode of operation to that shown in Fig. 32.

While I have shown and described in detail the preferred forms of devices, it will be understood that, except as specifically defined in the claims, my invention is not limited to the precise form or construction shown as equivalent devices will be apparent to those skilled in the art.

I claim:—

1. In combination, two rotatable switch members having movement in substantially the same plane, a locking bolt pivotally mounted between the switch members for movement in substantially the same plane and means on the bolt and the switch members for affording an interlocking engagement.

2. In combination, two rotatable switch members having movement in substantially the same plane, a locking bolt pivotally mounted between the switch members for movement in substantially the same plane and means on the bolt and the switch members for affording an interlocking engagement, the bolt being substantially tangent to the switch members at the point of engagement.

3. In combination, two rotatable switch members having movement in substantially the same plane, a spring indexing device, a locking bolt pivotally mounted between the switch members for movement in substantially the same plane and means on the bolt and the switch members for affording an interlocking engagement.

4. In combination, two rotatable disk-shaped switch members having movement in substantially the same plane, a locking bolt pivotally mounted between the switch members and extending tangentially to the switch members, means on the switch members and on the bolt for interlocking the same, said means being so constructed and arranged that substantially the whole force applied to the switch members in either direction is transmitted to the bolt in the direction of the axis thereof, and means resisting unlocking movement of the bolt.

5. In combination, two rotatable disk-shaped switch members having movement in substantially the same plane, a locking bolt pivotally mounted between the switch members and extending tangentially to the switch members, means on the switch mem-

- bers and on the bolt for interlocking the same, said means being so constructed and arranged that substantially the whole force applied to the switch members in either 5 direction is transmitted to the bolt in the direction of the axis thereof, means for moving the bolt to locking and to unlocking position and means resisting movement of the bolt from one position to the other.
- 10 6. In combination, two rotatable disk-shaped switch members having movement in substantially the same plane, a locking bolt pivotally mounted between the switch members and extending tangentially to the 15 switch members, means on the switch members and on the bolt for interlocking the same, said means being so constructed and arranged that substantially the whole force applied to the switch members in either 20 direction is transmitted to the bolt in the direction of the axis thereof, means for moving the bolt to locking and to unlocking position and spring means operative to resist initial movement of the bolt from one position 25 toward the other position and to assist the final movement of the bolt in either direction.
7. In combination, a rotatable switch member provided with locking elements, a locking-bolt having cooperating locking elements, means for moving said bolt towards and from its locking position and spring-operated means for causing the bolt to complete its locking and unlocking movement.
- 30 8. In combination, a rotatable switch member provided with locking elements, a locking-bolt having cooperating locking elements, means for moving said bolt towards and from its locking position and spring-operated means for causing the bolt to complete its locking and unlocking movements, comprising a rigid member and a spring member, one carried by the bolt and the other stationary.
- 35 9. In combination, a rotatable switch member provided with locking elements, a locking-bolt having cooperating locking elements, means for moving said bolt towards and from its locking position and spring-operated means for causing the bolt to complete its locking and unlocking movements, comprising a rigid member and a spring member, one carried by the bolt and the other stationary, the rigid and spring members having oppositely inclined or curved engaging surfaces.
- 40 10. In combination, a rotatable switch member provided with locking elements, a resilient locking bolt having cooperating locking elements, a stationary abutment having curved or inclined surfaces and located in proximity to said switch member, and a member on said bolt having oppositely inclined or curved surfaces.
- 45 11. A rotatable switch member having a circumferentially extending flange, a central boss, locking grooves in the surface of the flange on the boss-side and recesses in the face of the boss for receiving a spring member.
12. A rotatable switch member formed to define a central boss, a circumferentially extending flange, locking grooves in the boss-side of the flange and recesses in the face of the boss, and a spring member having parts disposed in the said recesses.
13. A rotatable switch member formed to define a hub-portion, a manipulating portion at one side thereof, a flange portion at the other side thereof, a central boss extending beyond the flange and recesses in the face of the boss for receiving a spring member.
14. A switch device comprising an escutcheon plate, a base plate, two rotatable switch members, and a common oscillatable locking device, the switch members and locking device being rotatably held in substantially the same plane between and by the said plates.
15. A switch device comprising an escutcheon plate, a base plate, two rotatable switch members and a common oscillatable locking device, the switch members and locking device being freely journaled on said escutcheon plate and held in substantially the same plane in place by the base plate.
16. A switch device comprising an escutcheon plate, a base plate, two rotatable switch members and an oscillatable locking device, the escutcheon plate having openings therein in which the switch-members are journaled and having thereon a pivot for the locking device, the base plate having thereon means for holding the locking device on its pivot and a surface having contacts with which the springs engage, and means carried by said plates for freely journaling the switch members and locking device between said plates.
17. A switch device comprising an escutcheon plate, a base plate, two rotatable switch members and a common oscillatable locking device disposed in substantially the same plane, and means carried by said plates for freely journaling the switch members and locking device between said plates.
18. A switch device comprising an escutcheon plate, a base plate, two rotatable spring switch members and an oscillatable locking device, the escutcheon plate having openings therein in which the switch-members are journaled and having thereon a pivot for the locking device, the base plate having thereon means for holding the locking device on its pivot and a surface having contacts with which the springs engage.
19. A switch device comprising an escutcheon plate, a base plate, a rotatable spring switch member and an oscillatable locking device, the escutcheon plate having

- openings therein in which the switch-member is journaled and having thereon a pivot for the locking device, the base plate having thereon means for holding the locking device 5 on its pivot and a surface having contacts with which the spring engages, and means carried by said plates for freely journaling the switch members and locking device between said plates.
- 10 20. The combination of a base plate carrying a plurality of circularly disposed contact elements and a rotatable switch member comprising a body portion, a handle portion, a circular flange portion having a plurality of inwardly extending grooves, a central boss and spring arms on the boss extending beyond the periphery thereof and carrying at its outer ends contact members adapted to contact with the said contact 15 elements, means for holding the switch member and the contact elements in operative relation and a locking bolt movably mounted relatively to the plate for engaging said grooves.
- 20 25. 21. The combination of a base plate carrying two circular groups of contact elements, two rotatable switch members comprising each a body portion, a handle portion, a circular flange portion having a plurality of inwardly extending grooves, a central boss and spring arms on the boss extending beyond the periphery thereof and carrying at its outer ends contact members adapted to contact with one group of contact elements, 30 means for holding the switch members and the contact elements in operative relation and a bolt pivotally mounted intermediate its ends and carrying at its ends teeth adapted to engage said grooves.
- 35 40. 22. In a device of the class described, the combination with an escutcheon plate having a key hole, of a base plate having molded therein a cavity shaped to receive the barrel of a lock.
- 45 50. 23. In a device of the class described, the combination with an escutcheon plate having a key hole, of a base plate having molded therein a cavity shaped to receive the barrel of a lock and a cavity defining a journal bearing for a locking bolt.
- 55 60. 24. A base-plate having molded therein a cavity shaped to receive the barrel of a lock, and a projection having adjacent to and concentric with said cavity a curved surface adapted to prevent undue downward movement of the bit of the key.
- 65 65. 25. The combination with an escutcheon plate having an opening therein, a slotted lock-barrel extending into said opening, a base-plate having therein a cavity to receive the barrel, and a projection on said base-plate having adjacent to and concentric with said cavity a curved surface adapted to prevent undue downward movement of the bit of the key.
- 70 26. In a device of the class described, a base-plate having molded therein a cell for receiving switch members and a locking device, a cavity for receiving the barrel of a lock and a cavity defining a journal bearing for a locking device.
- 75 27. In a device of the character described, a base-plate having molded therein a cell for receiving switch members and a locking device and defining a marginal flange adapted to form a seat for an escutcheon plate, the said base-plate having molded therein a cavity for receiving a barrel of a lock and a cavity defining a journal bearing for a locking device.
- 80 28. In a device of the character described, a base-plate molded to define two cells for receiving two switch members, an intermediate cell for receiving a locking bolt, a cavity for receiving the barrel of a lock, a cavity forming a journal bearing for the locking bolt and a marginal flange adapted to form a seat for an escutcheon plate.
- 85 29. In a device of the character described, a base-plate molded to define two cells for receiving two switch members, an intermediate cell for receiving a locking bolt, a cavity for receiving the barrel of a lock, a cavity forming a journal bearing for the locking bolt and a marginal flange adapted to form a seat for an escutcheon plate, the base-plate also having molded therein contact members extending from the outer surface of the base-plate into the cells.
- 90 30. In a device of the character described, a base-plate molded to define two cells for receiving two switch members, an intermediate cell for receiving a locking bolt, a cavity for receiving a barrel of a lock, a cavity forming a journal bearing for the locking bolt and a marginal flange adapted to form a seat for an escutcheon plate, the base-plate also having molded therein contact members extending from the outer surface of the base-plate into the cells, and a cavity in each cell adapted to form a journal bearing for the switch member.
- 95 35 40. 31. In a device of the character described, a base-plate molded to define two cells for receiving two switch members, an intermediate cell for receiving a locking bolt, a cavity for receiving the barrel of a lock, a cavity forming a journal bearing for the locking bolt and a marginal flange adapted to form a seat for an escutcheon plate, the base-plate also having molded therein contact members extending from the outer surface of the base-plate into the cells, a cavity in each cell adapted to form a journal bearing for the switch member and an arcuate depression in each cell concentric with the said last mentioned journal bearing, adapted to co-operate with a projection on the switch member to limit angular movement thereof.

32. In a device of the character described, the combination with an escutcheon plate carrying two rotatably mounted switch members, a locking bolt mounted for oscillating movement between the switch members and a key barrel adjacent the locking bolt, of a base plate molded to define cells for the switch members, a cell for the locking bolt, a cavity for the key barrel, a journal bearing for supporting the locking bolt and a flange forming a seat for the escutcheon plate.
33. In a device of the class described, a locking bolt comprising a central pivot portion, resilient arms extending therefrom, a locking tongue near the end of each arm and a portion on one arm deflected out of the plane thereof.
34. In a device of the class described, a locking bolt comprising a central pivot portion, resilient arms extending therefrom, a locking tongue near the end of each arm and a portion at the end of one arm deflected out of the plane thereof.
35. In a device of the class described, a locking bolt comprising a central pivot portion, resilient arms extending therefrom, a locking tongue near the end of each arm, a portion on one arm deflected out of the plane thereof and means on the central portion defining a key-engaging surface.
36. In a device of the class described, a locking-bolt comprising a central perforated portion, and resilient arms extending therefrom, each arm having a locking tongue and an end portion having inclined surfaces.
37. In a device of the class described, a locking-bolt comprising a central perforated portion, and resilient arms extending therefrom, each arm having a locking tongue and an end portion having inclined surfaces.
38. An oscillatable locking bolt having a central pivot portion, arms extending therefrom, a locking tongue on each arm, key-engaging faces on the central portion disposed at an angle to each other, one of said faces being engaged when the key is turned in one direction and the other of said faces being engaged when the key is turned in the other direction.
39. An oscillatable locking bolt having a central pivot portion, arms extending therefrom, a locking tongue on each arm, key-engaging faces on the central portion disposed at an angle to each other, one of said faces being engaged when the key is turned in one direction and the other of said faces being engaged when the key is turned in the other direction, and means on the central portion for preventing the key to be turned in the wrong direction.
40. A locking-bolt comprising a central perforated portion and arms extending therefrom, each arm having a locking tongue and an end portion deflected out of the plane of the arm and defining oppositely inclined surfaces.

In testimony whereof I affix my signature 70
in presence of two witnesses.

EDWARD WESTON.
